UNITED STATES PATENT OFFICE

2,653,026

AERIAL TARGET

Abram M. Feltus, Washington, Miss.

Application March 20, 1950, Serial No. 150,785

1. Claim. (Cl. 273—105.4)

1

This invention relates to novel and useful improvements in a target, and more specifically pertains to improvements in a clay or similar skeet target or the like.

The principal object of this invention is to provide an improved skeet target and the like which will more quickly and accurately evidence the accuracy of a hit upon the target by a gunner.

A further object of the invention is to provide an improved skeet target which shall greatly increase interest in trap shooting by the effects of hits of different accuracies upon the target.

Yet another object of the invention is to provide an improved clay pigeon which shall be inexpensive, of the same overall size and appearance as conventional targets, and yet shall be modified to obtain a vastly different effect in response to hits of various accuracies by shooters.

These, together with various ancillary features and objects of the invention, which will later become apparent as the following description proceeds, are attained by the present invention, preferred embodiments of which have been illustrated, by way of example only, in the accompanying drawings, wherein:

Figure 1 is a side elevational view of a clay pigeon suitable for use with the present invention;

Figure 2 is a top plan view of the target of Figure 1;

Figure 3 is a vertical transverse sectional view taken substantially upon the plane indicated by the section line 3—3 of Figure 1, an element of the invention being removed therefrom;

Figure 4 is a side elevational view of the element of the invention removed from Figure 3;

Figure 5 is a view similar to Figure 3 but showing the clay pigeon and a fibrous pad secured thereto in accordance with this invention;

Figure 6 is a group assembly view showing a shattering of the target and the separation of the mass of fibrous material therefrom as a result of a direct hit upon the center portion of the target;

Figure 7 is a view similar to Figure 6 but showing the result of a partial hit upon the target; and

Figure 8 is a top plan view of one of the layers or laminations forming a part of the fibrous pad of Figure 4.

Referring now more specifically to the accompanying drawings, wherein like numerals designate similar parts throughout the various views, there is indicated generally at 10 a skeet or clay pigeon of conventional design and construction such as customarily employed in trap shooting

2

and the like and to which the present invention is to be applied. This target consists of a clay or other frangible body or unit, the same being bowl-shaped and provided with a concaved surface 14, the unit having a central web portion 12.

Indicated generally by the numeral 16 is a mass of fibrous material constituting a pad which, in accordance with the principles of this invention, is to be attached to the web portion 12 of the frangible body 10. This mass of fibrous material 16 may conveniently consist of a plurality of substantially circular laminations, layers or sheets of a felt-like material or any other material of a similar nature which is of a fluffy, lightweight character.

The pad 16 may conveniently be formed as by securing a plurality of sheets or layers 18 together and sewing, stapling or otherwise fastening the layers into a pad as by stapling, fastening or similar means indicated generally at 20 in Figure 4. In any event, it is intended that the plurality of layers or sheets of material shall be secured together and act as a unit for attachment to the clay pigeon 10, as set forth hereinafter.

It is further to be considered that the invention comprehends the fastening of a plurality of sheets together, as by adhesives, or the like, but preferably, as shown in Figures 3, 5 and 6, a fastening means such as a conventional form of brad or the like 22 is provided, the same having a headed portion 24. This brad is intended to be inserted through an axial opening in the web 12, the headed portion 24 resting on the exterior surface of the web as shown in Figure 3, and the split shank of the brad extending into the interior of the clay target pad and extending through central apertures 26 in the sheets 18, so that by bending the ends of the brad the layers of the pad will be secured together and the entire pad secured to the under surface of the web 12 as shown in Figure 5.

Preferably, the layers 18 of the web are of such size that the same will be secured and received entirely within the cavity or concaved surface 14, with the periphery of the sheets terminating in spaced relation to this surface as clearly disclosed in Figure 5.

Alternatively, the pad may be secured to the web by such means as adhesives, or the like.

With the device arranged as in Figure 5, it will be seen that the separate pad element has been attached to a conventional clay pigeon and is entirely housed and received therein, whereby the operation of the pigeon is handled by a trap machine and its flight through the air will not

be affected by the presence of the pad. However, when a direct hit has been made upon the center of the target, that is, upon the web portion 12, this web will be shattered, as shown in Figure 6, and the pad 16 will then fall freely to the ground. However, if only a partial hit has been made upon the target, as shown in Figure 7, only a portion of the rim of the target will be destroyed, and the web portion 12 will remain substantially unbroken, with the pad 16 attached thereto. In this instance, the motion of the target will continue as shown by the arrows in Figure 7, and the pad will be carried with the target.

In either event, the light, fluffy nature of the pad will be more readily distinguishable during dropping of the pad or of the unbroken portion of the target to the ground, and will thus serve to indicate the accuracy of the hit. In other words, upon a direct or full hit upon the target, the pad will be completely released and its fluffy nature will stop further progress of the same in the direction of flight of the target, so that the pad will drop directly to the ground beneath the hit. However, in the case of a partial hit, the fluffy pad will be carried by the unbroken portion of the target and will thus be moved onwardly in the line of flight of the target and will fall to the earth at a considerable distance from the location where the target was hit. By means of this construction, it will be much easier to determine the accuracy of a hit, and the number of hits which a shooter makes, thereby greatly facilitating interest in and enjoyment of trap shooting.

From the foregoing, the construction and operation of the device, together with its advan-

5 tages, will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claim.

Having thus disclosed and described the invention, what is claimed as new is as follows:

15 A skeet target comprising a conventional dish-shaped clay pigeon having a central web portion and a pad of fibrous material attached to said web portion within the confines of the clay pigeon, said pad consisting of a plurality of layers of a felt-like material of a fluffy, light-weight character, the attachment being by means 20 of a single metallic fastener extending through the pad and the web portion.

ABRAM M. FELTUS.
